BAG CONSTRUCTION

George R. Clipner, 5516 Howard St., Omaha, Nebr.
Filed July 27, 1959, Ser. No. 829,747
2 Claims. (Cl. 229—56)

This invention relates to product packaging and more particularly to multiple compartmented bags for the packaging of potato chips and the like.

Heretofore the conventional method of doing such packaging has been to have a single outer bag and two completely separate and independent inner bags disposed in but not attached to the outer bags.

With this prior art method it has been necessary for the two inner bags to be separately filled, separately sealed, and then inserted into the outer bag by hand, and to which the outer bag is itself sealed. For these reasons the cost of the end product is very great and the labor force necessary for these sealing and stuffing operations is considerable.

An object of my invention is to provide a bag having two separator walls forming two separate inner compartments which are preferably formed in one operation whereby the separator walls are securely positioned and sealed in the bag.

Another object of this invention is to provide a bag of the character described whereby the inner compartments are filled separately but wherein both of the inner compartments and also the bag itself are sealed in one operation eliminating the prior art process of separately sealing two inner bags and inserting them into the outer bag and then sealing the outer bag, totalling three sealing operations.

The reduction of time consumption, labor cost and the increase of efficiency in cutting three sealing operations down to one is immediately apparent.

A further object of the invention is to provide a means of making a multi-compartment bag in which two sleeves are suitably secured to the bag at its lower end, and if desired also at its upper end so as to divide the bag into two separate compartments, with the sleeves as the innermost lining thereof.

Yet another object is to provide a bag having a double dividing wall providing greater strength.

Still another object is to provide modifications in which the dividing walls above described are disposed in bags of single wall thickness or of double wall thickness, and in both of which modifications great savings in labor are achieved over the prior art methods.

Still another object is to provide means whereby both inner separator walls are firmly fixed into position with respect to a single or double thickness bag by having the lower edges of the walls folded upwardly inside of the upwardly folded lower edge of the outer bag, with the upwardly folded lower edge portions all firmly held in such positions by suitable means thereby firmly closing the lower end of the resultant multi-compartmented bag and also firmly closing the compartmenting walls in place in the bag.

Still another object of the invention is to provide a multi-compartmented bag the inner compartments of which are sealed simultaneously with the sealing of the bag by means of folding of the upper terminal edges.

Yet another object is to provide a bag as described in which the sealing is done by hermetically sealing the upper and lower terminal edges together by applying coatings of heat sealing material and then applying heat to cause fusion of the various layers.

Yet another object is to provide a method of more rapidly making multi-compartmented bags by the unrolling of a sheet of material to form the bag and the simultaneous

2

taneous unrolling of (a) one folded sheet, or (b) or of two or more folded sheets forming inner compartments, or (c) the unrolling of sleeves of annular shape forming the one or more inner compartments, with the sheet of material forming the bag being simultaneously and continuously wrapped around the inner compartment forming material to the end that its edges are overlapped whereby they can be sealed together then or later, making possible the efficient cutting off to proper bag lengths simultaneously both inner compartment forming material and the bag material itself, and thereafter the simultaneous and continuous folding and sealing of the inner separator material and the bag itself at the bottom—and at the top, after filling, all preferably as above described.

Other and further objects and advantages of the present invention will be apparent from the following detailed description, drawing and claims, the scope of the invention not being limited to the drawings themselves as the drawings are only for the purpose of illustrating a way in which the principles of this invention can be applied.

Other embodiments of the invention utilizing the same or equivalent principles may be used and structural changes may be made as described by those skilled in the art without departing from the present invention and the purview of the appended claims.

In the drawings:

FIG. 1 is a frontal elevation of a multi-compartmented bag of this invention;

FIG. 2 is a view-in-section taken along the line 2—2 of FIG. 1;

FIG. 3 is a view-in-section taken along the line 3—3 of FIG. 1, with a portion broken away;

FIG. 4 is a top plan view showing a method of simultaneously unrolling material for forming walls or separators and other material forming a bag itself;

FIG. 5 is a perspective view showing the relative position of the separator and the outer sheet of material which forms the bag with the sealed longitudinal overlapping edges of the bag forming material being spread apart to reveal the shape and position of the inner separators;

FIG. 6 is a view showing a stage in the method of closing the lower ends of the bag by folding;

FIG. 7 is a perspective view of a modified bag which has been completed in all respects except the sealing of its upper end;

FIG. 8 is a view showing a modified method of sealing the lower edges of both separator wall material and the bag itself by heat fusion employing coatings of heat sealing material to form a hermetically sealed joint;

FIG. 9 is a view-in-section of a modified bag which in external appearance would be like the bag of FIG. 1, but FIG. 9 shows a bag having a double outer wall and a double wall divider;

FIG. 10 shows a cross-section of a modified bag, the section being similar to that of FIG. 9 but showing a bag having a single-thickness outer wall and also a single separator wall.

Referring to FIG. 1 we there see the exterior of a multi-compartmented bag 10 of this invention. The bag 10 comprises a bag 12 and is best seen in FIG. 2, and further comprises a plurality of inner separators or sleeves 14 two of which are shown by way of example in FIG. 2.

The outer bag 12 has its sides 20 folded inwardly and the sides of the inner sleeves or tubular or sleeve-like partitions 14, seen at 24, are also folded inwardly whereby the resulting multi-compartmented bag is easily folded or collapsed by further and similar folding.

It will be seen that each of the sleeves 14 forms a compartment of the resulting total multi-compartmented bag.

It is preferred that the forward and rearward walls 30 of the inner sleeves 14 lie adjacent and in touching relation.

tionship and in parallelism with the forward and rearward walls 32, 32' of the bag 12.

Similarly it is preferred that the end walls 24 of the inner sleeves 14 lie parallel to and closely adjacent or touching the end walls 20 of the bag 12.

Referring to FIG. 3, it will be seen that the lower edges of the inner sleeves 14 and the bag 12 are preferably collapsed and folded upwardly as best seen at 40 and are then folded downwardly as best seen at 42 to form a double fold with the lower edges of the inner sleeve 10 substantially co-extensive with the lower edges of the bag. The double fold can be maintained in any suitable manner such as by placing heat sealing material between the several layers and applying heat and fusing the layers together.

The upper ends of the bag can be similarly secured as best seen in FIG. 3 in which the upper terminal edges are folded over and downwardly as best seen at 50, also with the upper terminal edges of the inner sleeves materially extending co-extensive with and folded downwardly 20 with the upper terminal edges of the bag.

The folded relationship with the upper end of the bag can be maintained with staples 52 or can be maintained by hermetic sealing similarly to the lower edge.

Likewise the single folded upper terminal edge shown 25 in FIG. 3 will serve to illustrate a way in which the lower terminal edge could also be closed by a single fold.

Referring to FIG. 4 we there see a method of efficiently forming a multi-compartmented bag in which one or more rolled up masses or rolls of annular inner sleeve material, generally indicated at 60, are being unrolled from a common axle 62 for simultaneous and uniform and even unrolling with the rolls 60 and 62 being preferably 30 of equal diameter at all times.

As the inner sleeve material 60 is unrolled a flat sheet 35 of rolled material 70 is simultaneously being unrolled about its axle 72 and is being unrolled in the same direction as the roll 60 and is at the same time folded around the under side of the unrolled portion 76 of each roll 40 60 until the side edges 78 of the flat sheet material overlap each other, this operation all being done as one continuous operation.

The resultant material can then be cut to desired 45 lengths for forming bags and such a piece of material already cut from the remainder is generally indicated at 80 in FIG. 4 and a perspective view of the composite material 80 is generally indicated in FIG. 5, and in which the edges of the overlapped portion 78 of the outer bag or flat sheet material 70 are spread upwardly to show the annular inner sleeve material 60 therebeneath.

It will be seen that the overlapping edges 78 are provided with suitable sealing means 80 and are sealed together where they overlap, preferably in one continuous operation before the cutting off of sections like the section 80, although such sealing of the edges 80 could be done after cutting, also.

Referring to FIG. 5 it will be seen that the inner annular bag material 60 itself each is provided with overlapping edges 88 which latter are preferably provided therebetween with suitable means for facilitating their cementing or sealing whereby they are either cemented or hermetically fused together by the application of heat or coatings of heat seal material as is a sealing method that can be employed on almost any of the secured edges of the bags shown in this application.

It will be seen that it is preferred that the overlapping edges 88 be secured together before the pieces of material 60 are placed on the axle 62.

Referring to FIG. 5 it will be seen that when the sealing of the edges 78 is done after the cutting into a section 80, then it is easier to place sealing material 90 on the forward and rearward side of the inner sleeve material 60 whereby the overlapping edges 78 of the outer bag can then be sealed together with a later sealing operation binding the inner sleeves to the walls of the outer bag 70 75

by means of sealing or cementing material 90 and application of heat or other means.

Other and similar sealing is preferably done on the opposite side of the inner sleeve materials.

5 Referring now to FIG. 6 we see our next step in the method which is the folding over of the lower terminal edge 96 of the outer bag material 70 with cement or coatings of heat-seal material 98 applied to all surfaces of the folded over material which would be inwardly disposed after a complete folding has been finished, in the case of the method shown in FIG. 6 a double folding is to be done which will result in a finished bag having cross-sectional appearance at its lower end similar to that shown in FIG. 3.

Other modifications of the multi-compartment bag of this invention can be made and one is shown in FIG. 7 in which a double thickness laminated bag is generally indicated at 100 having overlapped edges 102, the outer thickness having an inner layer or thickness 106 laminated thereto or loose therein except at the bottom and top.

In the modification of FIG. 7 a wall means or separator wall or partition 110 is disposed suitably attached by hermetic sealing, by cement or otherwise, as generally indicated at 112 to the forward and rearward sides of an inner layer or inner bag 106, the forward and rearward terminal edges of the wall 110 being disposed transversely to the remainder of the wall so as to be parallel to the forward and rearward walls 120 and 122 respectively of the inner bag 106.

The wall 110 divides the inner layer 106 of the bag 100 into two completely separate compartments and the wall 110 preferably is folded at its lower end so that it is flat and is folded preferably vertically along a line transverse to the upturned and folded lower edge 130 of the composite bag formed of the outer bag 100 and inner bag 106.

The wall 110 is upturned and folded in with the upturned lower edge 130 of the outer bag 110 which also has in it the upturned lower edge of the inner layer or sleeve 106, is therefore bound in such a way as to completely separate two compartments 140 and 142 from each other.

It will be seen that the lower edge 130 of the bag 100 is folded upwardly only and is not double-folded as is another possibility.

Referring now to FIG. 9 we there find an outer bag layer 150 and an inner bag layer 152 and a divider or wall means or separator wall means 160. The divider or wall or wall means 160 in this modification is an annular sleeve and forms a double separator wall with two sides 162 and 164 which are secured together by having common ends 168 disposed transversely thereto and which are disposed parallel to the face and back walls 170 and 172 of the inner bag layer 152.

55 The double wall means or dividers can similarly be folded at their lower ends in the folded lower end of the entire composite bag similar to other modifications as is believed not to need further illustration for that reason.

Referring to FIG. 10 we have a bag having a single outer wall 190 and provided with a divider or wall means or separator wall 190 having a single thickness with vertically extending ends 194 which latter fit flat against the face and back walls 196 and 198 of the bag 190; the single wall means 192 dividing the bag into two completely separate compartments 200 and 202.

FIG. 8 illustrates another way separate wall means 222 can be secured by being folded and inserted between the bottom ends of the folded outer bag 190 as another modification. FIG. 8 is a view of a bottom of a bag 220 having an inner separator wall portion 222 folded at 223.

The lower terminal edges of the bag 220 and the separator wall 222 of the modification of FIG. 8 are not folded over to form a seal but instead have a suitable cement or heat-sealing material generally indicated at 240

therebetween whereby, upon the application of heat, the various coatings of heat-sealing material 240 and the wall 222 and bag 220 are all sealed together in heat fusion.

It will be seen that this method of sealing can be used in the upper or lower edges of any of the bags herein although it is preferred in many cases that the upper edges be simply folded and stapled for greater ease of opening.

It will also be seen that any suitable adhesive is included in the term "cement" as used with any of the bags or modifications herein. Further it will be seen that any suitable material can be employed for these bags, such as wax paper or the like, the particular material not being of significance.

Referring now again to FIG. 1 it will be seen that dotted diagonal lines 250 can be employed to indicate lines along which the upper end of the bag can be opened, the dotted lines 250 being imprinted in a suitable manner into the bag material itself.

A take-apart, two section bag can be made by optionally perforating the multi-compartment bag 150 of FIGURE 9 with perforations 270 completely around its periphery from the top of the face, down the face through folded bottom parts, up the rearward side and through all parts folded at the top, not shown. The perforations lie along a vertical plane through the bag.

The bag of FIGURE 9, thus weakened by the perforations, can be torn apart to use one bag conveniently at a time. Yet there is enough strength to hold both sections together in normal handling.

It will further be seen that the bag 150 of FIGURE 9 can have its two outer walls completely laminated together giving the appearance of one single wall, the two outer walls being formed from paper which is of a two lamination, double thickness.

It will be seen that the upper and lower ends of the bag have closure means attached thereto for maintaining the bag ends substantially sealed and for maintaining the partition sealed to the upper and lower bag ends for closing the compartments formed by such partition against moist outer air and against the passage of air from one of said compartments to the other to maintain the contents of the bag crisp. Such closure means can be either sealing material as at 240 as seen in FIGURE 8 or staples 52 as seen at the top of FIGURES 1 and 3 and either combined with folding as shown at the top of FIGURE 3 or multiple folding as seen at the bottom of FIGURE 3.

I claim:

1. A multi-compartmented package comprising a bag for crisp food products, said bag having forward and rearward sides attached together at their adjacent portions and disposed in parallelism at their upper and lower ends, a plurality of sleeves in said bag, said sleeves having closed sides and having upper and lower ends disposed in parallelism with and between the said upper and lower ends of said tubular bag, and closure means attached to the ends of said bag and maintaining said bag ends and said partition ends sealed together for economically closing said sleeves so as to form inner bags.

2. A multi-compartmented package comprising a bag for crisp food products, said bag having forward and rearward sides attached together at their adjacent portions and disposed in parallelism at their upper and lower ends, two spaced partitions in said bag, said partitions each having sides attached to opposite sides of said bag for dividing said bag into compartments sealed from each other, each said partition having its upper and lower ends disposed in parallelism with and also disposed between the said ends of said tubular bag for economical separation of said compartments, each said partition being of such size as to be folded when said package is flattened, and closure means attached to the ends of said bag and maintaining said bag ends and said partition ends substantially sealed together for closing said compartments against entry of moist air to maintain the contents crisp, whereby if a user tears said bag between said partitions one of said compartments can be maintained closed for maintaining the contents crisp while the other said compartments can be torn open for access thereto.
